United States Patent Office

Des. 184,564
Patented Mar. 10, 1959

184,564

LAMP

Irmi Ann Gross, New York, N. Y.

Application February 28, 1958, Serial No. 49,840

Term of patent 3½ years

(Cl. D48—20)

Fig. 1

Fig. 2

Figure 1 is a front perspective view of a lamp showing my new design.

Figure 2 is a reduced top plan view thereof with the shade omitted for convenience of illustration.

The sides of the shade not shown are the same in appearance as the sides shown.

I claim:

The ornamental design for a lamp, substantially as shown and described.
